UNITED STATES PATENT OFFICE.

FRANS HENDRICKX, OF CHICAGO, ILLINOIS, ASSIGNOR TO HENRY M. MITCHELL, OF CHICAGO, ILLINOIS.

DISPLAY-CABINET.

SPECIFICATION forming part of Letters Patent No. 730,209, dated June 2, 1903.

Application filed February 10, 1902. Serial No. 93,428. (No model.)

To all whom it may concern:

Be it known that I, FRANS HENDRICKX, a citizen of the United States of America, and a resident of Chicago, in the county of Cook and State of Illinois, have invented certain new and useful Improvements in Display-Cabinets, of which the following is a specification.

The main objects of my invention are to provide an improved cabinet having therein a plurality of tablets suitable for displaying samples—such as fabrics, pictures, &c.—said tablets being adapted to be withdrawn from said cabinet and turned from side to side to permit the convenient display of the articles secured thereto, to provide for conveniently examining the texture of the mounted samples both on the front and the reverse side thereof, and to provide a suitable structure permitting said tablets to be entirely removed from said frame for greater convenience in attaching said articles to their surfaces. I accomplish these objects by the device shown in the accompanying drawings, in which—

Figure 1 is a perspective view of a display-cabinet constructed according to my invention, showing two of the tablets withdrawn from said cabinet and turned on their hinges to display the fabrics attached to the surfaces of said tablets. Fig. 2 is a transverse section of the cabinet, showing the construction of same. Fig. 3 is an elevation of a form of hinge suitable for connecting the display-tablets to their corresponding slides in said cabinet.

The device shown consists of a rectangular box or frame 1 open at the front and having secured to its upper and lower interior surfaces a series of parallel guides 2, which are regularly spaced. The spaces between the guides 2 form ways 3, within which the slides 4 are movable. The ways at the top of the cabinet correspond to those at the bottom, so that the slides 4 are supported in a vertical position. To each of the slides 4 a display-tablet 5 is hinged by means of the pintles 6 and the gudgeons 7. This form of hinge permits the tablets 5 to be easily disconnected from the slide 4. The front ends of the ways 3 are closed by the stops 8, which prevent the slides 4 from being entirely withdrawn from

said ways. A picture or a sample of fabric 9 is secured to each side of each tablet 5. The faces of the tablets near their front edge are provided with notches 10, which serve as handles for withdrawing the tablets 5 from the cabinet 1. The recesses 11 in the front edge of each tablet 5 provide means whereby the texture of the fabrics displayed may be examined on both sides without loosening the tacks by means of which said fabrics are secured. As shown in the drawings, it is found convenient to cut a notch in the fabric on one side of the tablet corresponding to the upper recess 11 and to cut the fabric on the other side of the tablet 5 to correspond with the lower recess 11. The guides 2 are preferably made somewhat deeper than the stops 8, so that when the tablet 5 is pushed backwardly into the frame 1 said tablet will be confined by said guides against swinging laterally on its hinges.

The operation of the device shown is as follows: Samples of fabrics are secured to each face of each of the tablets 5. Said tablets are connected with their corresponding slides 4 and pushed backwardly into the cabinet. All of the samples will now be neatly housed within the cabinet. When it is desired to examine one of said samples, the corresponding tablet 5 is withdrawn from the cabinet and turned so that the desired sample may be seen from the front. The texture of said sample may be tested at one of the notches 11. If it is desired to display said sample in connection with some article in another part of the room, the tablet 5 may be readily lifted from its gudgeons without disturbing the remainder of the cabinet.

It will be seen that some of the details of the device shown may be altered without departing from the spirit of my invention. I therefore do not confine myself to such details except as hereinafter limited in the claims.

What I claim as my invention, and desire to secure by Letters Patent, is—

1. A display-cabinet comprising a frame having a series of strips, forming ways, therein, slides seated in said ways and adapted to slide therein, a tablet hinged to said slide

and having a plurality of cut-away portions on its forward edge, and suitable stops limiting the movement and preventing the removal of said slides, the tablets being adapted to move along in said ways when in the frame and capable of lateral movement to right or left when withdrawn from the frame, said tablets adapted to have material tacked thereon overlapping the cut-away portions so the material can be inspected.

2. A display-cabinet comprising a frame having a series of ways arranged therein, slide-pieces adapted to slide therein, tablets detachably hinged to each of said slides and having a plurality of cut-away portions in its forward edge, each of said slides being adapted to be moved along said ways a sufficient distance to allow said tablet to be withdrawn from said frame permitting said tablet to move laterally to right or left or to be entirely detached from its slide, said tablets adapted to have material tacked thereon over-

lapping the cut-away portions so the material can be inspected.

3. A display-cabinet comprising a frame having a series of strips forming ways, slides running in said ways, tablets hinged to said slides and running in said ways and having a plurality of cut-away portions on its forward edge, stops connected to said frame preventing the removal of said slides, said way-forming strips being thicker than the stops which permits the tablets to run therein, and prevents lateral movement thereof when inserted in the frame, said tablets adapted to have material tacked thereon overlapping the cut-away portions so the material can be inspected.

Signed at Chicago this 8th day of February, 1902.

FRANS HENDRICKX.
